APPARATUS FOR CHARGING AND SEALING
METALLIC BULBS

Herbert F. Tomasek, St. Louis, Mo., and Lawrence T. Ward, East Orange, N. J., assignors, by mesne assignments, to Knapp-Monarch Company, St. Louis, Mo., a corporation of Delaware

Application June 15, 1945, Serial No. 599,594

6 Claims. (Cl. 219—4)

1

Our present invention relates to an apparatus for charging and sealing metallic bulbs of the kind shown in Weida application, Serial No. 535,893, filed May 16, 1944, now Patent No. 2,425,448, dated August 12, 1947, and Ward application, Serial No. 587,454, filed April 10, 1945, now abandoned.

One object of the invention is to provide an apparatus of this character which can be manually initiated as to its operating cycle and will thereafter automatically charge the bulb with gas and weld the metallic cover on the bulb to form an integral bulb and cap combination after which the bulb may be removed from the apparatus.

Another object of the invention is to provide a pressure chamber around the neck of the bulb, to receive the neck with a cap thereon, and into which any desired gas under pressure, such as carbon dioxide (CO₂) or nitrous oxide (N₂O), or any combination thereof, may be introduced for charging the bulb, and the cap may then be welded on the bulb while they are still in the pressure chamber.

Still another object is to provide an apparatus of this character which is provided with an automatic sequence timer to cause a repeated cyclical operation of all parts of the apparatus after the first cycle is initiated manually.

A further object is to provide for operating various parts of the apparatus in proper sequence and for the proper periods of time to fully charge the bulb, weld the cover to the bulb with a welding current of the proper duration and provide thereafter a forging period of proper duration.

Still a further object is to provide a sequence timer control for the apparatus wherein the completion of certain operations cause the subsequent operations to occur in their proper order.

With these and other objects in view, our invention consists in the construction, arrangement and combination of the various parts of our device whereby the objects contemplated are attained, as hereinafter more fully set forth, pointed out in our claims and illustrated in the accompanying drawings, wherein:

Fig. 1 is a side elevation of the apparatus embodying our present invention;

Fig. 2 is a front elevation thereof;

Fig. 3 is an enlarged sectional view on the line 3—3 of Fig. 1, showing the parts in one position (filling the bulb with gas).

Fig. 4 is a similar sectional view showing the parts in another position (welding the cap to the bulb).

2

Fig. 5 is a sectional view on the line 5—5 of Fig. 3 showing a gas valve;

Figure 5a is an enlarged sectional view through the top of the bulb and the cap; and

Fig. 6 is a diagrammatic view showing our apparatus and including a schematic diagram of a complete cycle of operation thereof and the relation of the operations of different elements of the apparatus during such cycle.

On the accompanying drawings we have used the reference character F to indicate a frame of our apparatus on which is mounted a rotatable table T and a head H. The head H is normally in the position of Fig. 1 but is mounted for movement downwardly from this position, the head for this purpose being secured to a boss 13 mounted within a clamp 12 of a piston rod 14. The piston rod 14 is connected with a piston or ram R¹ located within a cylinder 16.

20 The head H includes a cylinder 18 in which is mounted a secondary piston or ram R² with which is connected a piston rod 20. The piston rod 20, as shown in Fig. 3, has an electrode 22 in its lower end, and the table T has a plurality of bulb seat elements 24 projecting upwardly therefrom which also serve as electrodes, as will hereinafter appear and which are equally spaced around the center of rotation 26 of the table T.

25 The head H has therein a pressure chamber 28 into which the electrode 22 projects after passing through an insulation bushing 30. The electrode 22 is a taper fit as at 32 in the lower end of the piston rod 20 and may be removed therefrom for replacement by inserting a drill press wedge into 30 a slot 34 of the piston rod 20 and tapping on it to drive an expeller pin 36 downwardly in the manner standard on drill presses.

35 The electrode 22 is preferably a good working fit in the bushing 30 and, consequently, pressure from the chamber 28 can pass through the bushing. This pressure is sealed off from atmosphere by a diaphragm of rubber, "neoprene" or the like, and the diaphragm is of washer-like character and of the cross-section shown in Fig. 3. Its outer edge is sealed in the head H by a gland 40 and its inner edge is sealed relative to the piston rod 20 by a fiber ring 42 and a lock nut 44. Shims are provided at 46 to regulate the pressure of the seal around the periphery of the diaphragm 38 45 when the head H is held in position by screws 48 threaded into an enlarged outer end 15 of the boss 13.

In the lower end of the head H is a sleeve-like plug 50 for sealing against a bulb B below a cap 55 C on the bulb when the parts are in the position

of Fig. 3. A valve GV is provided for admitting gas under pressure to the pressure chamber 28 and is shown particularly in Fig. 5. The gas valve GV comprises a valve seat 52 against which a valve pin 54 is adapted to seat. Seating is effected by rotating the valve pin 54 as the pin is threaded, as indicated at 56. A lever 58 is mounted on the valve pin and is connected by a link 60 to a solenoid plunger 62. The plunger is adapted to be lowered by gravity and raised by energization of a solenoid coil S³. Gas under pressure may be supplied to the gas valve GV as from a supply hose 66. This gas may be any kind suitable for charging the bulb B such as carbon dioxide or nitrous oxide or some combination of the two.

In connection with the pressure chamber 28, the sleeve 50 may have an insert 51 of Bakelite or fiber, which preferably seats slightly imperfectly on the bulb B. This permits escape of a slight amount of gas which, due to its expansion, tends to keep the bulb cool. In this way dissipation of the heat caused by filling and welding the bulb is facilitated by the escaping gas. Inasmuch as the lower end of the piston 20 moves into the head H, there will be displacement of gas below the diaphragm 38. This is taken care of by permitting the gas to escape through a bleeder screw 68 screwed into a vent passageway 70. The bleeder screw has a groove of proper size in its side to permit escape of gas at the desired rate.

For supporting actuating fluid, such as compressed air, to the cylinders 16 and 18 for operating the rams R¹ and R², the valves V¹ and V² are provided, as shown diagrammatically in Fig. 6. The valves are illustrated in the position for raising the rams and may be reversed in position for lowering the rams by energization of solenoids S¹ and S², respectively. The valves may subsequently be returned to initial position by solenoids S⁴ and S⁵.

We have also shown diagrammatically in Fig. 6 a welding switch WS for supplying current through leads 86^b and 88^a to the electrodes 22 and 24, respectively, and a switch S controlled by the presence of bulbs in the seat elements 24 for recycling the welding apparatus as long as the table T is supplied with bulbs.

The various control elements just described are interconnected with a plurality of timers such as T¹, T², T³, T⁴ and T⁵, which may be of the electronic type, the apparatus for which is mounted in the housings 90 and 92 and the current wires from which extend through a conduit 94 to the frame F. We have shown merely a diagrammatic arrangement in Fig. 6 for the timers in relation to time periods and the elements of the welding apparatus, as will herein-after be more fully explained in the description of the operation which follows.

In connection with the bleeder screw 68 there is some escape of carbon dioxide which is in the liquid phase from the chamber 28 past the electrode 22 through the bushing 30, and this gradually escapes through the vent 70 and the slot in the side of the screw 68. Of course, as it expands into the atmosphere it becomes a gas, and this effects enough refrigeration action to keep the carbon dioxide in the liquid phase within the chamber 28.

Practical operation

In the operation of our bulb charging and sealing apparatus the operator places empty bulbs B in the bulb seat elements 24 with the caps C loosely mounted on the bulbs. When the table 75

T has been rotated by suitable means until one of the bulbs strikes the arm of the switch S the cycle of operation of the machine commences, the switch controlling the timers T¹ and T² and the solenoid S¹, as indicated by the dotted line 72 and the solid lines 74 and 76. The dotted lines in Fig. 6 indicate the control of one element from another, and the solid lines indicate time periods, which periods are named along the left side of Fig. 6, and which are separated at the time points A, B, C, D, E, F, G and H. For instance, the time point A indicates that the ram R¹ starts on its downward movement, this, of course, being due to the solenoid S¹ being energized. At time point B, timer T¹ is energized, which results in the ram R² starting downward under control of the solenoid S². By this time the ram R¹ is down. Also, at time point B the timer T² is energized, which, after a time period ending at point C, when the ram R² is down, causes the gas valve GV to open, due to energization of the solenoid S³ under control of the timer T³. The gas valve will subsequently be closed at time point C', or any time between it and time point E', this timing being variable, so that the gas is cut off before the welding current is on, during the time the welding current is on, or after it is cut off. The timer T³, after a further time period, ending at time point D, operates timer T⁴ which turns the welding current on at the welding switch WS so that current then flows across from the electrode 22 through the cap C and the bulb B to the seat 24. The parts at this time, of course, are in the position of Fig. 4, and at time point E the welding current is cut off by the timer T⁵, opening the welding switch WS. At time point F the timer T⁵ effects energization of the solenoids S⁴ and S⁵ for causing the rams R¹ and R² to start upwardly, and at point G the timer T⁵ causes the table T to be operated as through a Geneva movement of the usual type. At point H the Geneva movement stops and the switch S is operated to start the next cycle at A again, providing there is a bulb in position at the switch S. Thus, as long as bulbs are fed to the apparatus, the machine continues to operate and will automatically stop when there are no bulbs. The operating cycles will be repeated indefinitely, until a master control is operated for cutting off the current supply.

50 The time periods are shown substantially equal in length, but are not necessarily so. Each time period can be adjusted as desired, as usual with electronically timed welding apparatus. Where the timers are electronic tubes they are sequentially operated, as, for instance, the timer T³ being operated by the timer T² when it times out its period, the timer A⁴ being operated by timing out of the period for T³, and so on. For closing the gas valve at anywhere from point C' to E', the timer T³ may de-energize the solenoid S² at the point where the circuit decays. Likewise, the circuit for the timer T⁵ may decay at G' so that the Geneva movement, started at G, will continue through its complete cycle of operation, usually controlled by mechanical means, and stop at point H and cause the table to stop at the time point indicated as H, just previous to which the switch S will have been operated if there is a bulb in the seat 24 at that position. Since electronic weld timer controls are well known in the art, we have not attempted to go into detail as to the necessary hook-up, describing only the inter-related operations in the complete cycle of operation for our apparatus.

55 Describing the operation of the machine a little

more in detail, lowering of the ram R^1 lowers the head H , so that the sleeve 50 engages the shoulder of the bulb B below the cap C thereon, as shown in Fig. 3, to substantially seal off the compartment 28 from atmosphere. The bulb is now ready to be charged and, accordingly, it is desirable to open the gas valve GV at this time.

After the valve is opened the gas therefrom enters the chamber 28 and fills the bulb, passing readily under the loose cap. When the electrode 22 is lowered and the welding current turned on, the weld period ensues, which weld period follows a squeeze period, during which the cap is held under pressure on the bulb. After the weld current is off, a hold period is provided for forging the weld, as it has been found that, after the weld is completed, the welded joint will be stronger if held for a period of time. The forging or hold period is terminated by the rams R^1 and R^2 , raising to open the compartment 28 and during a clearing period wherein the chamber 28 clears the bulb B , there is no movement of the table T . Instead, the table moves only during the Geneva period which occurs after the chamber 28 has cleared the bulb, and when the Geneva movement has completed one cycle of its operation the entire recycling of the machine is in order.

Our apparatus provides a convenient means to charge metallic bulbs and weld metallic caps thereon all within a pressure chamber of minimum dimensions so that there is the least possible waste of gas discharged to atmosphere when the forging period has been completed and the head H is raised. The apparatus operates automatically to seal the pressure chamber with respect to each bulb as it comes into position at the charging and welding station and requires only the initiation of a cycle after which the cycles are repeated automatically and all functions performed in their proper order as long as there are bulbs in the machine.

The welding current is preferably supplied to the electrodes only during the peaks of the alternating current wave to secure greatest efficiency in a manner also well known. It is desirable to have the timers adjustable for the purpose of adapting the apparatus to most efficient operation, depending upon the surrounding humidity and temperature conditions. As these conditions vary, the possible speed of operation of the apparatus will also vary, and it is best to have it operate at its highest possible speed as thus a maximum of bulbs can be charged per unit of time. As far as an operator is concerned, he can readily feed one or more machines with empty bulbs and remove the filled ones as fast as the machines can perform the charging and welding operations.

Some changes may be made in the construction and arrangement of the parts of our device without departing from the real spirit and purpose of our invention, and it is our intention to cover by our claims any modified forms of structure or use of mechanical equivalents which may be reasonably included within their scope without sacrificing any of the advantages thereof.

We claim as our invention:

1. In an apparatus for sealing metallic necked bulbs, a bulb seat element adapted to have a bulb seated therein with a metallic cover loose on the bulb, a head movable relative to said bulb seat element and adapted to imperfectly seal against the neck of the bulb below said cover and thereby constitute a chamber surrounding said

neck, an electrode movable relative to said head and engageable under pressure with said cover, a diaphragm connection between said electrode and said head to seal off said chamber from atmosphere and permit movement of said electrode relative to said head, and means for supplying welding current to said electrode and said bulb seat element whereby to weld said cover to said bulb while the bulb from its neck up and said cap are under pressure in said chamber.

2. In an apparatus for sealing gas pressure bulbs of the necked type, a bulb seat element adapted to have a bulb seated therein with a cover loose on the bulb, a head movable relative to said bulb seat element and adapted to seal against the neck of said bulb and thereby constitute a chamber surrounding said neck, an electrode movable in said head and engageable with said cover, means to seal off said chamber from atmosphere and permit movement of said electrode relative to said head, and means for supplying welding current to said electrode and said bulb seat element whereby to integrally weld said cover to said bulb.

3. An apparatus for sealing metallic bulbs having necks comprising a movable support having a plurality of bulb seats therein, said support being movable to successively position said bulb seats at a station, said bulb seats adapted to have bulbs seated therein with metallic covers loose on the bulbs, a head movable relative to said support at said station and adapted to seal against the neck of a bulb at said station, an electrode movable relative to said head and engageable with said cover, and means for supplying welding current to said electrode and said support.

4. In an apparatus for sealing metallic bulbs, a bulb seat element adapted to have a bulb seated therein with a metallic cover loose on the bulb, a head movable relative to said bulb seat element and adapted to seal against the bulb wall below the cover thereon, an electrode movable relative to said head and engageable under pressure with said cover, and means for successively moving said head downwardly to seal against said bulb wall, moving said electrode downwardly to engage said cover with said bulb under pressure, pass an electric welding current through said electrode and bulb seat element to weld the cover to the bulb, hold the pressure of the electrode on the bulb during a forging period, and raise the electrode and head to permit removal of the sealed bulb from the bulb seat element.

5. An apparatus for sealing bulbs comprising a bulb seat element adapted to have a bulb seated therein with a cover on the bulb, a head movable relative to said bulb seat element and adapted to seal against the bulb below the cover thereon, an electrode movable relative to said head and engageable under pressure with said cover, means for moving said head downwardly to seal against said bulb, and timed means for successively moving said electrode downwardly to engage said cover with said bulb under pressure, passing an electric welding current through said electrode and bulb seat element to weld the cover to the bulb, holding the pressure of the electrode on the bulb during a forging period, and raising the electrode and head to permit removal of the sealed bulb from the bulb seat element.

6. An apparatus for sealing metallic bulbs comprising a plurality of bulb seat elements, a mov-

able support therefor, a head movable relative to said support and adapted to seal against a bulb in one of said seats below a cover on the bulb, an electrode movable relative to said head and engageable under pressure with said cover, means to manually initiate downward movement of said head and thereafter successively and automatically move said electrode downwardly relative to said head to engage said cover with said bulb under pressure, pass an electric welding current through said electrode and support to weld the cover to the bulb, hold the pressure of the electrode on the bulb during a forging period, raise the electrode and head to permit removal of a sealed bulb from the support, and move said support for positioning another bulb seat beneath said head, and timers to control

the movement of said electrode and the timing of the welding and forging current periods.
